ATTORNEY.

UNITED STATES PATENT OFFICE

CORTLAND W. DAVIS, OF OAK PARK, ILLINOIS, ASSIGNOR TO THE MANTLE LAMP COMPANY OF AMERICA, OF CHICAGO, ILLINOIS, A CORPORATION OF ILLINOIS

FLAME SPREADER

Original application filed July 25, 1927, Serial No. 208,286. Divided and this application filed October 18, 1928. Serial No. 313,287.

This application is a division of the application of Cortland W. Davis, #208,286, for a Blue flame mantle lamp, filed July 25, 1927, in which are revealed several improvements all of which co-operate to control the functioning of the burner with which a lamp of that type is provided, whereby it is possible to reduce the creeping or working-up tendency of the flame, to obtain a full light from the lamp in a short period of time, and to render the operation of the lamp stable and reliable.

Among these several features of construction are a new chimney and its retaining means, a new flame spreader, a new burner cone construction, a new flame-protecting baffle, a new mantle head and a new mantle supporting means. The disclosure and the claims of this application relate to the new flame spreader.

This spreader is of the type having perforated cylindrical and frusto-conical sections, and is distinguished by the absence of the air obstructing and relatively wide web of metal heretofore present at the junction of these two perforated sections. By the elimination of said web of metal the spreader distributes air currents uniformly throughout its entire perforated areas, and also removes an air-obstructing factor from the most advantageous point for air delivery.

The invention will be best understood if this specification be read in connection with the accompanying drawing in which—

Figure 1 is a vertical sectional view of a burner containing the improved spreader;

Figures 2 and 3 illustrate the flame spreader shown in Figure 1, and

Figure 4 shows a step in the process of manufacturing the completed spreader shown in Figures 2 and 3.

The flame spreader 29 (Figures 1, 2, 3) which is supported in the upper end of the inner wick tube 1, has a cylindrical body 50, and a frusto-conical wall 51, both of which are provided with minute perforations 52 through which air flowing upward from the central air passage of the lamp bowl and through said inner wick tube 1, may pass.

The distinguishing features of this flame

spreader are, first, continuity of the perforated areas of the cylindrical body 50 and the frusto-conical wall 51, which are not, as in other flame spreaders, separated by a narrow heat-absorbing and air-obstructing bridge of metal; and, second, a depressed central portion 53 of frusto-conical form which, being somewhat removed from the high-temperature combustion zone, is kept relatively cool so that it will conduct little heat to the inner wick tube. Said central portion 53 operates to uniformly deflect the rising air currents towards all the aforesaid perforations of the spreader, thus facilitating flow of said currents through said perforations and into the flame; and this depressed central portion has a perforation 54 of suitable size, the object thereof being to prevent induced low-pressure conditions within it and the consequent drawing of the flame against the spreader. The employment of a flame spreader of this design, tends to prevent overheating of the inner wick tube, maximizes the quantity of air supplied to the interior of the flame and renders uniform the distribution of air emanating from both the cylindrical and the frusto-conical area of the spreader.

The process of making the new flame spreader consists in first producing a cylinder (Figure 4) having an imperforate lower portion 55, a perforated upper portion 56 in which the number and size of the holes are the same as those of the completed spreader 29, and a flat and imperforate top wall 57.

The upper extremity 58 of the cylinder is also imperforate.

The cylinder, thus produced, is subjected to the action of dies whereby the top wall 57 is drawn and depressed, and so much of the cylinder as includes said upper extremity 58 and the uppermost row 59 of the perforate portion 56, is shaped to assume the form shown in Figures 2, 3. The perforation 54 is then made.

Having thus described my invention what I claim is:

1. A flame spreader for a burner of the blue-flame wick type having a perforated frusto-conical portion, a cylindrical wall

having perforations adjacent said frustro-conical portion, and a depressed top.

5 2. A flame spreader for a burner of the blue-flame wick type having frustro-conical portion, a cylindrical wall having perforations adjacent said frustro-conical portion, and a depressed top provided with a pressure-equalizing hole.

10 3. A flame spreader for a burner of the blue-flame wick type having a cylindrical wall provided at its upper end with perforations, and having also a perforated frustro-conical portion adjoining the top of said cylindrical wall, the perforations in said cylindrical wall and the perforations in said frustro-conical portion constituting a continuous series of air-emitting openings, all of which openings are substantially equidistant from each other.

15 4. The process of producing a flame spreader having a cylindrical wall, a frustro-conical portion adjacent the top of said wall, and a depressed top which consists in producing a blank having a cylindrical wall and a flat top, and subjecting said blank to a drawing operation whereby the upper portion of said cylindrical wall is shaped to frustro-conical form and the central portion of said top wall is at the same time drawn to form said depressed portion.

In testimony whereof I affix my signature.
CORTLAND W. DAVIS.
